UNITED STATES PATENT OFFICE.

AMOS REEVES AND ALFRED W. JOHNSON, OF ROCK FALLS, ILLINOIS.

BOOT OR SHOE CLEANER.

SPECIFICATION forming part of Letters Patent No. 600,376, dated March 8, 1898.

Application filed March 12, 1897. Serial No. 627,153. (No model.)

To all whom it may concern:

Be it known that we, AMOS REEVES and ALFRED W. JOHNSON, citizens of the United States, residing at Rock Falls, in the county 5 of Whiteside and State of Illinois, have invented certain new and useful Improvements in Boot or Shoe Cleaners; and we do declare the following to be a full, clear, and exact description of the invention, such as will enable 10 others skilled in the art to which it appertains to make and use the same, reference being had to the accompanying drawings, and to the figures and letters of reference marked thereon, which form a part of this specification.

15 Our invention relates to boot and shoe cleaners, and refers more specially to that class of such devices covering a scraper for removing mud from the shoes and a brush attachment therefor. The principal features 20 of our invention are simplicity, compactness, and protection of the brush from the weather.

In the drawings, Figure 1 is a side elevation of our invention when in use. Fig. 2 is a similar view of our device when not in use.

25 Fig. 3 is a cross-section in the line $x-x$ of Fig. 2. Similar figures and letters refer to similar parts in all the drawings.

1 is the usual mud-scraper, supported on the plate 2, which is rigidly secured to the 30 step or walk where it is to be used. On the plate 2, at one end of the scraper 1, are rigid standards 3, to which is hinged, as at a , the brush-holder 4, of the same length as the scraper. The brush-holder 4 is provided with 35 a projection 5, by means of which it can be operated. The free end of the brush-holder when closed rests upon the standard 6 at that end of the scraper 1 opposite the standards 3. Within the brush-holder is secured an ordinary wooden-backed brush 7, either by means 40 of a screw passing through the brush-holder into the back of the brush or by any other suitable method.

As the main part of our device can be constructed in two parts of cast-iron it can be 45 cheaply manufactured.

When desired to use our device, the brush is thrown back by catching the toe under the projection 5 and raising the brush-holder.

After scraping and brushing the shoes it can 50 be closed in the same way. Not only does the brush-holder 4 serve as a protection for the brush when our invention is closed, but in closing the same the end of the brush-holder falling upon the standard 6 jars the 55 dirt out of the brush 7 and keeps it clean.

When not in use, the device takes up little more room than the scraper alone would occupy.

What we claim as our invention, and desire 60 to secure by Letters Patent of the United States, is—

1. In a boot and shoe cleaner, the combination, with a base or plate provided with a longitudinal scraper and an abutment at one 65 end, of a cover pivotally secured to the other end, the free end of the cover being provided with a projection for closing or opening the cover, the cover being adapted to lie even with the base when open and to extend over 70 it when closed, and a brush secured to the interior of the cover, substantially as set forth.

2. In a boot and shoe cleaner, the combination, with a base or plate, one end of which is 75 provided with an abutment, and the opposite end is provided with ears, said base being provided with a scraper extending longitudinally thereof, a box-like cover provided with curved arms pivotally secured to the ears at 80 one end and having its opposite end provided with a projection adapted to engage with and project beyond the abutment at the end of the base when the cover is folded over the plate, the top of the cover being adapted to 85 lie even with the base when open, and a brush secured to the interior of the cover, substantially as set forth.

In testimony whereof we affix our signatures in presence of two witnesses.

AMOS REEVES.

ALFRED W. JOHNSON.

Witnesses as to Reeves:

JAMES C. WINTERS,
CHAS. T. DEETS.

Witnesses as to Johnson:

MAURICE D. JOHN,
JNO. H. BYERS.
